UNITED STATES PATENT OFFICE.

JOHN O. BROWN, OF ALLERTON, IOWA.

STUMP-PULLER.

1,160,038.

Specification of Letters Patent. Patented Nov. 9, 1915.

Application filed March 22, 1915. Serial No. 16,108.

To all whom it may concern:

Be it known that I, JOHN O. BROWN, a citizen of the United States, residing at Allerton, in the county of Wayne and State 5 of Iowa, have invented certain new and useful Improvements in Stump-Pullers; and I do declare the following to be a full, clear, and exact description of the invention, such as will enable others skilled in the art to 10 which it appertains to make and use the same.

This invention relates to improvements in stump pullers and more particularly to the class having interchangeable parts.

15 The object of the invention is to provide a stump puller so constructed that the speed or power may be increased or decreased at the will of the operator, by changing the position of the sweep whereby a great saving 20 in time and labor may be effected.

With this and other objects in view, the invention consists of certain novel features of construction, and the combination and arrangement of parts as will be hereinafter 25 more fully described and claimed.

30 In the accompanying drawings: Figure 1 represents a side elevation of a stump puller constructed in accordance with this invention showing it applied; Fig. 2 is a plan view thereof; Fig. 3 is a longitudinal vertical section taken on the line 3—3 of Fig. 2. Fig. 4 is a sectional view of the drum giving same one-fourth turn from the position shown in Fig. 3; Fig. 5 is a side elevation 35 partly in section of the shaft 13 giving same one-fourth turn from the position shown in Fig. 3. Fig. 6 is a horizontal sectional view taken substantially on the line 4—4 of Fig. 3.

40 In the embodiment illustrated a supporting frame is shown comprising a base plate 1 mounted on transversely extending cross bars 2 and 3 which project at their opposite ends beyond the opposite sides of said base 45 plate and thus afford a reliable support for the device. Rising from the opposite ends of the base plate 1 are two standards 4 and 5 to one of which a guy rope 6 is designed to be connected and after being so connected 50 is connected with a suitable support for anchoring the apparatus in the desired position. The plate 1 is provided with longitudinally spaced bearings 7 and 8 for a purpose to be described.

55 A top plate 9 connects the upper ends of the standards 4 and 5 and is provided with

longitudinally spaced bearings 10 and 11 which are positioned to register with the bearings 7 and 8 in the base plate and which are adapted to interchangeably receive 60 shafts 12 and 13 which are preferably of a length somewhat longer than the distance between the upper ends of the top plate 9 and the lower face of the base plate 1 for a purpose to be described. The upper end of 65 the shaft 12 is enlarged at 15 and this enlargement is provided at its upper end with an integral gear 14. The lower end of the enlarged portion is provided with a clutch member in the form of notches 16 which 70 are designed to coöperate with a clutch member carried by a drum to be described. The end of the shaft 12 carrying the gear 14 is provided with a socket 17 which is here shown circular in cross sectional contour but it may be angular if desired and opening from the side walls of this socket 17 are angular recesses 18 which are designed to receive lugs 19 which project laterally from the opposite sides of an axle 20 carried 80 by a sweep 21 as will be hereinafter more fully described.

The bearings 7 and 8 in the bottom plate 1 are smaller than those 10 and 11 in the top plate 9 to adapt them to snugly receive the 85 lower ends of the shafts 12 and 13 while the bearings in the top plate are designed to receive the enlargement 15 carried by the shaft 12 or a similar enlargement 15' carried by the shaft 13. The shaft 13 is enlarged at 15' and this enlarged portion is provided at its upper side with an integral gear 25 which is about twice the diameter, more or less, of that of the gear 14 and is adapted to mesh with said gear 14 when in 90 operative position. This enlargement 15' has angular notches 16' in its inner end to form a clutch member which are adapted to coöperate with a corresponding or coöperating clutch member carried by the drum 30. 100 This shaft 13 is also provided in the end which carries the gear 25 with a socket 17' which is similar in shape to the socket 17 of the other shaft 12 and is provided at its opposite sides with angular recesses 18' communicating with the socket and which are designed to receive the lugs 19 of the axle 20 of the sweep 21.

The sweep 21 is provided with a lever 22 herein shown bail or U-shaped with the free 110 ends of the arms thereof secured to cams 23 pivotally mounted on the opposite side edges

of said sweep 21. These cams are adapted to bear against the upper or outer face of the gear carried by the shaft to which the sweep is applied and to disengage the pins 19 from the notches 18 when the lever 22 is thrown backwardly, whereby the drums may be revolved freely by a pull on the cable 36 to be hereinafter described. The hollow winding drum 30 is herein shown for interchangeable engagement with either of the shafts 12 or 13 as may be desired and this drum is provided on its inner face at opposite sides thereof adjacent one end with laterally extending studs 31 which are positioned to enter the notches 16 or 16' of the clutch members of the shafts 12 or 13 according to which the drum is to be connected and thereby fixedly connect said drum with the shaft and adapt it to be rotated therewith for a purpose to be described. This drum 30 is provided at its opposite ends with the usual flanges 32 and 33, the flange 33 at the upper end of the drum having ratchet teeth 34 in its peripheral edge which are designed to be engaged by a spring pressed locking dog 35 mounted on the lower face of the top plate 9 near one end thereof and which is designed to lock the drum 30 against unwinding during the changing of the sweep 21 from one shaft to the other. A cable 36 is secured at one end to the drum 30 and is adapted to be wound thereon after the other end thereof has been connected with the stump to be extracted and the winding of this cable on said drum produces the pulling effect on the stump which withdraws it from the ground.

From the above description it will be obvious that when the axle 20 of the sweep 21 is placed in one of the sockets of one of the shafts 12 or 13 that the turning of this shaft will through the intermeshing gears rotate the drum 30 and wind up the cable 36 thereon when turned in one direction and when turned in the opposite direction said cable may be unwound, but for unwinding the cable it is desirable to disengage the sweep from the apparatus and to unwind it by exerting a pulling action on the free end thereof. When it is desired to rotate the drum for unwinding the cable it is preferred that the gears 14 and 25 should be thrown out of mesh so that the shaft only on which the drum is mounted will be rotated and thereby avoid any unnecessary wear on the parts of the apparatus, and to provide for this purpose a lever 37 is fulcrumed on the top plate 9 at a point adjacent one of the shafts. This lever is fulcrumed intermediately of its ends and its inner end is designed to be inserted under the gear adjacent which it is mounted and by exerting a downward pressure on its free outer end this gear will be raised together with the shaft on which it is mounted a sufficient distance to disengage it from the

other gear and the cable may be then freely unreeled without turning the other gear.

With the parts assembled for speed as shown in Fig. 1 the shaft 12 carrying the small gear 14 is shown extending through the drum 30 and connected therewith by the engagement of its clutch member 15 with the coöperating clutch carried by the drum, said drum and shaft 12 being shown mounted in the bearings 7 and 10 of the base and top plates. The shaft 13 carrying the other gear 25 is shown mounted in the bearings 8 and 11 and the sweep is connected with the socket 17' of said shaft 13, the axle 20 of said sweep being inserted in said socket and rigidly connected therewith by the engagement of the laterally extending studs 19 with the recesses 18' adjacent said socket 17'. By the turning of this sweep 21 it will be obvious that the speed of rotation of the drum will be twice that of the rotation of the shaft 13 with which the sweep is connected owing to the difference in the size of the two gears 14 and 25.

When it is desired to produce what may be termed single power the parts remain in the position shown in Fig. 1 except that the sweep 21 is disengaged from the shaft 13 and inserted in the socket 17 of the shaft 12 and the shaft 13 with its gear 25 are preferably removed from the bearings 11 and 8 to prevent the unnecessary wearing of said gear by the turning of shaft 12.

To provide what may be termed double power the parts being in the position shown in Fig. 1, the shaft 12 is removed from the bearings 7 and 10 and out of the drum 30 and inserted in the bearings 8 and 11 and the shaft 13 carrying the large gear is inserted in the bearings 7 and 10 and passed through the drum 30 and connected therewith by the engagement of the coöperating clutch members carried by said drum and shaft. The sweep 21 is then engaged with the socket 17 in the shaft 12 and by turning said sweep a slow moving action is produced on the drum and through the meshing of the small gear with the large gear double power on the drum is produced.

If desired when the sweep 21 is changed from the socket 17 of the shaft 12 carrying the small gear to the socket 17' of shaft 13 carrying the large gear the direction of movement of the team which is usually hitched to the free end of the lever or sweep 21 is reversed, thus producing an even wear on the lugs of the sweep and sockets and thereby prolonging the life of the apparatus.

From the above description it will be obvious that by changing the shafts 12 and 13 and connecting the sweep with one or the other of them as may be desired the speed of rotation of the drum may be increased or decreased and power applied thereto corre-

spondingly increased or decreased according to the wishes of the operator and that by the use of this apparatus much time may be saved and a great economy in labor may be effected.

I claim as my invention:

1. In a stump puller the combination of a supporting structure having vertically spaced plates provided with registering bearings, 10 shafts for interchangeable engagement with said bearings, gears carried by said shafts, the gear on one shaft being larger than that on the other, each shaft having a socket formed in one end thereof with communicating 15 recesses disposed at the sides of said sockets, a hollow drum adapted to be mounted in fixed relation on one of said shafts, a sweep having an axle extending laterally therefrom and provided with projections, 20 said axle being adapted to be inserted in the socket of one of said shafts and the projections thereon engaged with the recesses communicating with said socket, and a lever fulcrumed on said supporting structure with 25 one end positioned for insertion under an adjacent gear for raising said gear out of intermeshing engagement with the other gear.

2. In a stump puller the combination of vertically spaced plates having registering

bearings therein, the bearings in the upper 30 plate being larger than those in the lower, a pair of upright shafts interchangeably mounted in said bearings, said shafts having enlarged upper ends, said enlargements being provided with integral gears at their 35 upper ends and having their lower ends notched, a hollow drum disposed removably around one of said shafts and between said spaced plates, studs projecting inwardly from the inner sides of said drums 40 and positioned to enter the notches on the enlargements of said shafts for locking the drum to the shafts, said drum being provided with an integral annular flange at its 45 upper edge, said flange having ratchet teeth arranged on its periphery, a dog secured to the upper plate and engaging said ratchet teeth for holding the drum against retrograde movement, and an interchangeable sweep arm for revolving either of said 50 shafts.

In testimony whereof I have hereunto set my hand in presence of two subscribing witnesses.

JOHN O. BROWN.
